UNITED STATES PATENT OFFICE.

RALPH EDWARD OGDEN, OF MOUNTAINVILLE, NEW YORK, AND CHARLES C. TOMKINSON, OF PLAINFIELD, NEW JERSEY, ASSIGNEES TO JOHN EDWARD OGDEN, OF MOUNTAINVILLE, NEW YORK.

BOLT ANCHOR.

Application filed July 22, 1921. Serial No. 486,742.

This invention relates to improvements in bolt anchors of the character employed for obtaining anchorage in walls of brick or stone or cementitious material, not adapted 5 to directly receive a threaded bolt.

One of the objects of this invention is to provide a shield that may be set deep in the wall and need not extend to the outer end of the opening in the wall in order to be properly and firmly anchored therein.

Another object of the invention is to provide a shield so constructed as to form an abutment for the bolt upon the initial rotation of the bolt whereby the nut carried by the bolt will be fed along the bolt.

Another object of the invention is to provide an expansion shield and expanding means for the shield that is simple in construction, efficient in operation and may be 20 economically manufactured.

Another object of the invention is to provide a new and effective method of expanding an expansion shield.

Further objects of the invention will 25 appear from the following specification taken in connection with the drawings which form a part of the application.

The above objects are attained in the embodiment of the invention illustrated by a 30 shield comprising a plurality of parts or sections preferably of sheet metal or of uniform thickness, the shield having fingers or tines bent inwardly toward or approximately to the longitudinal axis thereof. 35 The fingers are adapted to be engaged by a bolt or threaded member upon the initial rotation thereof, thereby causing the nut carried by the bolt to travel along the latter and force the fingers outwardly or laterally 40 into engagement with the wall of the opening in which the shield is positioned.

Referring to the drawings:

Fig. 1 is a sectional elevation of a portion 45 of a wall having a bolt anchor, constructed in accordance with the invention, positioned therein, the expansion shield being expanded into wall engaging position.

Fig. 2 is a sectional elevation of the bolt anchor before the expansion of the shield.

Fig. 3 is an elevational view of the expansion shield.

Fig. 4 is an end elevation of the inner end 50 of the shield.

Fig. 5 is an end elevation of the opposite end of the shield.

Figs. 6, 7 and 8 are transverse sectional views taken substantially on lines 6-6, 7-7 and 8-8 respectively of Fig. 2.

Fig. 9 is a perspective view of the nut for expanding the shield.

Fig. 10 is an elevation of a single piece, sheet metal shield constructed in accordance with my invention.

Fig. 11 is an end elevation of the inner or bottom end of the shield shown in Fig. 10.

Fig. 12 is an end elevation of the other end of the shield shown in Fig. 10.

Fig. 13 is a plan view of the blank from which the shield shown in Fig. 10 is formed.

Fig. 14 is an elevation of another form 70 of single piece shield constructed in accordance with my invention.

Figs. 15 and 16 are end elevations of the two ends of the shield shown in Fig. 14, and

Fig. 17 is a plan view of the blank from 75 which the shield shown in Fig. 14 is made.

The expansion shield shown in Figs. 1-8 inclusive, comprises a shell divided longitudinally throughout its length forming sections 10 and 11. The sections are held 80 together by a split ring 13 positioned in grooves 14 formed in the sections of the shell. As shown in Figs. 1 and 2 the shell is formed of sheet metal stampings and the formation of the grooves provides supporting surfaces 15 for the bolt 16. The grooves 14 also form an internal shoulder or ridge which acts as a stop to limit the movement of the nut.

Each of the shells is slotted longitudinally 90 as shown at 17 and the metal at the edges of the slots adjacent the inner ends of the sections is cut away to form fingers or tines 18, these fingers being tapered as shown at 19 and also being tapered at their extreme ends 95 as shown at 20. The ends of the fingers or tines are bent inwardly as shown at 21 in a direction toward the longitudinal axis of the shield and in the embodiment of the invention illustrated the fingers extend substantially to the axis of the shield. The nut 22 which is adapted to receive a bolt 16 and to expand the shield into engagement with the wall of the opening may be made from a square bar on an automatic screw machine. 100 This nut has a plurality of flat faces 23 at

one end and these faces may intersect at a sharp angle or the corners may be cut off as shown at 24. The nut 22, as shown in Figs. 1, 2, 6 and 9, is a composite of prismatic and conical surfaces. The conical surfaces are disposed between the flat prismatic faces and taper from the corners 24 to the reduced cylindrical portion 25. The flat faces of the nut merge into a circular portion 25 at the opposite end of the nut, the diameter of this circular portion approximately equaling the inner diameter of the expansion shield. When the nut is placed in the shield the corners extend into the cut away portions between the fingers as shown in Fig. 6. The inturned ends 21 of the fingers retain the nut in the shield.

The shield shown in Figs. 10-13 inclusive is similar in finished form to that above described but in this instance the shield is formed from a single sheet metal stamping or blank 30. The blank 30 has slots 17 and fingers 18 similar to the corresponding parts in the other embodiment. The blank is folded upon itself and the side edges are bent laterally until they meet. The fingers 18 are bent inwardly toward the axis as shown in Figs. 10 and 11 at 21. An opening 31 for receiving the bolt may be punched in the blank before bending or may be punched after the blank has been folded to form the shield.

In Figs. 14-17 another single piece, sheet metal shield is shown. In this form, the central part 32 is reduced in size and is apertured. Fingers 18 are formed as before and the blank is folded about its central portion 32 and the edges are folded in to make the shield shown in Fig. 14.

The bolt anchor above described is operated in the following manner. When an object 26 is to be secured to a wall 27 the bolt 16 is passed through an opening formed in the object 26 and is threaded into the nut 22 which with the expansion shield has been inserted in an opening in the wall 27. Upon the initial rotation of the bolt 16 the end of the bolt will press against the bent ends 21 of the fingers or tines. The fingers thus form an abutment for the bolt and prevent longitudinal movement thereof. As the nut is rotated, therefore, the nut 22 will travel along the bolt to expand the anchor, and the fingers 18 will be pressed outwardly also by the sides of the bolt into firm and secure engagement with the wall of the opening. The tapered fingers are forced outwardly between the faces of the nut and the bore of the opening. The nut faces thus form chords in the circumscribing circle formed by the bore. The corners of the nut are forced into the cylindrical interior portion of the shield, thereby forcing this portion outwardly as shown in Fig. 1. It will thus be seen that the shield may be

deeply embedded in the opening in the wall and need not extend to the outer end of the opening or into engagement with the bar 26 in order to prevent the initial longitudinal movement of the bolt. When the head of the bolt engages the object 26 the nut will be further drawn along the bolt, further increasing the firmness of the anchorage, the parts taking approximately the position indicated in Fig. 1.

Although one specific embodiment of the invention has been particularly illustrated and described, it will be understood that the invention is capable of modification and that changes in the construction and in the arrangement of the various cooperating parts may be made without departing from the spirit or scope of the invention as expressed in the following claims.

What we claim is:

1. In combination, a shield having a substantially cylindrical inner surface and a plurality of longitudinally extending fingers with the ends thereof bent inwardly toward the axis of the shield, and a nut between said fingers, having a circular portion and a flat sided portion, adapted to engage a bolt and to expand said fingers.

2. In combination, a shield having a substantially cylindrical inner surface and a plurality of longitudinally extending fingers with the ends thereof bent inwardly toward the axis of the shield, and a nut between said fingers, having a circular portion with its diameter substantially equal to the inside diameter of the shield and a flat sided portion, adapted to engage a bolt and to expand said fingers.

3. In combination, a shield having a plurality of longitudinal slots forming a plurality of transversely tapered fingers, of uniform thickness throughout their length the ends of the fingers being bent inwardly toward the axis of the shield, and a nut between said fingers adapted to engage a bolt and to expand said fingers.

4. In combination, a shield having a substantially cylindrical inner surface, a plurality of longitudinally extending fingers with the ends thereof bent inwardly toward the axis of the shield, and a nut between said fingers, having a plurality of flat faces merging into a circular end portion, adapted to engage a bolt and to expand said fingers.

5. In combination, a shield having a substantially cylindrical inner surface and a plurality of longitudinal slots forming a plurality of separated fingers and a nut between said fingers having a circular portion and a plurality of flat intersecting faces forming corners extending into the slots.

6. In combination, a shield having a substantially cylindrical inner surface and a plurality of longitudinal slots forming a plurality of separated fingers, and a nut between

- said fingers having a circular portion and a plurality of flat intersecting faces forming corners extending into the slots and substantially to the outer circumference of the shield.
7. In combination, a shield of uniform thickness having a plurality of longitudinal slots forming a plurality of separated fingers, the ends of the fingers being bent inwardly, and a nut between said fingers having a plurality of flat intersecting faces forming corners extending into the slots.
8. In combination, a shield having a plurality of longitudinally extending, tapered fingers of uniform thickness and having a cylindrical inner surface and a nut having surfaces engaging said fingers and having corners adapted to engage and expand the cylindrical surface of the shield.
9. In combination, a shield having a plurality of longitudinally extending, tapered fingers of uniform thickness and having a cylindrical inner surface, and a nut having surfaces engaging said fingers and having corners extending between said fingers, said nut being adapted to engage and expand the cylindrical surface of the shield.
10. In combination, a shield having a substantially circular inner surface and a plurality of longitudinal slots forming a plurality of separated fingers, and a nut between said fingers having a circular portion and a plurality of flat intersecting faces forming corners extending into the slots.
11. In combination, a shield having a substantially circular inner surface and a plurality of longitudinal slots forming a plurality of separated fingers, and a nut between said fingers having a circular portion and a plurality of flat intersecting faces forming corners extending into the slots and substantially to the outer circumference of the shield.
12. A nut for expanding an expansion shield having flat surfaces extending substantially throughout the length of the nut and having surfaces extending substantially throughout the length of the nut and tapering from the flat surfaces to a circle.
13. A nut for expanding an expansion shield having a circular portion at one end and a flat sided portion at the other end and a tapered connecting portion extending substantially throughout the length of the nut.
14. In combination, a shield having expandable portions, and an expanding element therein, having tapered portions engageable with the shield, the expandable portions of the shield engageable by said element being disposed in a cylindrical surface coaxial with the axis of the shield.
15. In combination, an expansion shield having longitudinally tapered fingers of uni-
- form thickness and an expanding element having flat sides parallel to the axis of the shield and engageable with said fingers.
16. In combination, an expansion shield having a substantially cylindrical interior surface and a nut having a square end and tapered corners engageable with the cylindrical inner surface of the shield.
17. In combination, an expansion shield formed from metal of uniform thickness and having cylindrical interior portions and a nut having a polygonal end and having tapered corners engageable with the cylindrical interior portions of the shield.
18. An expansion shield having a plurality of expansible portions, a nut within said shield adapted to travel lengthwise therein and expand said portions, an internal stop shoulder in the shield engageable by the nut, and means on the outer surface of the shield adjacent the internal shoulder forming an excess of metal thereon.
19. In combination, a shield having a plurality of longitudinal slots forming a plurality of transversely tapered fingers of uniform thickness throughout their length, at least one of said fingers having its end bent inwardly toward the axis of the shield, and a nut between said fingers adapted to engage a bolt and to expand said fingers.
20. In combination, a shield having a plurality of longitudinally extending tapered fingers of uniform thickness, and an expanding member having flat faces parallel to the axis of the shield and engaging said fingers and adapted to force said fingers outwardly by the lateral wedging action of the flat faces on the tapered fingers.
21. In combination, an expansion shield having an internal ridge therein, reinforcing metal on the outer surface of the shield disposed in the plane of said ridge, and an expanding member in said shield, said ridge forming a stop for limiting the longitudinal movement of the expanding member in the shield.
22. In combination, an expansion shield comprising a substantially cylindrical tubular member of uniform thickness having longitudinally extending tapered portions, and an expanding member having flat surfaces substantially parallel to the shield axis and engageable with the edges of said tapered portions, and adapted to force said portions outwardly by a lateral wedging action.
- In witness whereof, I have hereunto set my hand this 18th day of July, 1921.
- RALPH EDWARD OGDEN.
- In witness whereof, I have hereunto set my hand this 18th day of July, 1921.
- CHARLES C. TOMKINSON.
